UNITED STATES PATENT OFFICE.

CHARLES O. REDMAN, OF GOTEBO, OKLAHOMA.

SIGNAL.

1,095,673.

Specification of Letters Patent.

Patented May 5, 1914.

Application filed March 20, 1913. Serial No. 755,764.

To all whom it may concern:

Be it known that I, CHARLES O. REDMAN, a citizen of the United States, residing at Gotebo, in the county of Kiowa and State 5 of Oklahoma, have invented certain new and useful Improvements in Signals; and I do hereby declare the following to be a full, clear, and exact description of the invention, such as will enable others skilled in the art 10 to which it appertains to make and use the same.

This invention comprehends improvements in signals and relates more particularly to those which are especially adapted 15 for use upon various kinds of vehicles so that the driver of a following vehicle may know that the preceding vehicle is going to make a turn.

The primary object of the invention resides 20 in the provision of a signal of this nature, which includes a lamp casing having a plurality of colored bull's-eyes, certain of which are normally covered by hinged plates or lids and are only exposed to view when a 25 turn is going to be made.

The invention also aims to provide a novel 30 combination of levers which may be actuated by the driver for swinging the before-mentioned lids so as to expose to view certain of the bull's-eyes.

With these and other objects in view, as 35 will become more apparent as the description proceeds, the invention consists in certain novel features of construction, combination, and arrangement of parts, as will be hereinafter described and claimed.

For a complete understanding of my invention, reference is to be had to the following description and accompanying drawings, 40 in which,

Figure 1 is a side elevation of an automobile, showing my improved signal applied thereto. Fig. 2 is a top plan view of my signal and operating means, Fig. 3 is a detail 45 side elevation of the lamp box and means for actuating the lids, the lamp box being shown partly broken away and partly in section. Fig. 4 is a front elevation of the lamp box, one of the lids being shown in its raised position, and, Fig. 5 is a detail perspective view of the other of said lids.

In the following description and accompanying drawings, similar parts will be referred to and designated by like characters 55 of reference.

Referring in detail to the drawings by

numerals, 10 designates, generally, an automobile to the rear of which a bracket 11 having the oppositely projecting arms 12, is suitably secured. A lamp casing, generally 60 designated 13, is attached to the rear end of the bracket 11 and has its outer wall 14 formed with three openings, over which are placed colored bull's-eyes 15, 16 and 17. These bull's-eyes are secured in position by 65 means of frames 17', carried by the inner side of the wall 14. The bull's-eye 15 is preferably colored blue, the bull's-eye 16 red, and the one designated 17 green. It is to be understood, however, that any other colors 70 may be used if desired, and that the lamp casing may be constructed somewhat differently from the form shown in the drawing.

18 designates an electric light which is positioned within the box and shines through 75 the various bull's-eyes. If desired, oil or gas may be used to furnish the proper illumination.

Lids or covers 19 and 20 are secured to the lamp casing by means of spring hinges 80 21 and are normally disposed against the wall 14 so as to cover the bull's-eyes 15 and 17 respectively. The cover 19 which is carried upon the left side of the lamp casing, has the word "Left" printed upon one side 85 thereof and the other cover 20 carries the word "Right". The covers may be actuated by any suitable means and for the purpose of illustration, I have shown a system of levers which includes the foot pedals 22, 90 rearwardly extending rods 23 pivotally connected at their forward ends to said pedals, and curved levers 24 which are pivotally connected intermediate their ends to the arms 12 of the bracket 11 and which are 95 connected to the rods 23. The levers 24 have their lower sections 25 disposed in a substantially vertical plane and their upper sections curved so as to extend over the lamp casing. Links 26 connect the rear ends of 100 the levers 24 to the covers 19 and 20. The lower ends of the links 26 are pivotally connected between ears 27 carried near the central portions of said covers.

When the vehicle is traveling continuously 105 in one direction and a turn is not contemplated, the lids 19 and 20 hide the bull's-eyes 15 and 17 and only the red bull's-eye 16 is exposed to view. When the vehicle is going to make a turn to the left the driver presses 110 forwardly upon the corresponding pedal 22 and the connecting rod 23 forces the lower

portion 25 of the curved lever 24 rearwardly. This motion causes the other end of said last mentioned lever to swing upwardly and raise the cover 19 so as to expose the blue 5 bull's-eye. The driver of a following vehicle will then know that the preceding vehicle is going to make a turn toward the left. As soon as the pressure is released from the foot lever, the spring hinge 21 will 10 return the cover to its normal position, at which time the bull's-eye is hid from view.

It is to be understood that while I have shown and described the preferred embodiment of my invention, that minor changes in 15 the construction of the lever and operating means, may be made without departing from the scope and spirit of the invention as defined by the appended claim.

Having thus described my invention, what 20 I claim is:—

The combination with a vehicle, of a signal device including a lamp casing formed

with an opening in the rear wall thereof, a lid, a spring hinge securing said lid to the casing so that it will normally cover the 25 opening formed therein, a lever pivoted intermediate its ends in front of the casing, one arm of the lever extending rearwardly over the casing, a link pivotally connected to the extremity of said arm and to the lid, the 30 other arm of the lever being disposed normally in a vertical plane and a longitudinally movable actuating rod pivotally connected to said last mentioned arm, a movement of the actuating rod rearwardly causing the lever to swing the lid upwardly and expose the opening formed in the lamp casing. 35

In testimony whereof I affix my signature in presence of two witnesses.

CHARLES O. REDMAN.
